UNITED STATES PATENT OFFICE.

FREDEERICK H. N. GERWIG, OF NORTH BRADDOCK, PENNSYLVANIA.

BOSH COOLING PLATE.

Application filed October 18, 1924. Serial No. 743,978.

This invention relates to cooling mechanism and more particularly to an improved form of bosh cooling plate and method of mounting the same.

- 6 One object of this invention is to provide an improved form of bosh plate having means to permit the passage of a sealing medium around the plate after it is mounted in the furnace wall.
- 10 Another object is to provide an improved form of bosh plate having a gasket retaining flange around its rear end to provide for a gasket seal to retain the sealing medium forced around the plate and to form a gas-
15 tight joint.

A further object is to provide a bosh cooling mechanism having the novel construction, combination, and design of parts hereinafter described and illustrated in the ac-
20 companying drawings.

Figure 1 is a sectional elevation taken on the line I—I of Figure 2.

25 Figure 2 is a top plan of a cooling plate embodying my invention.

Figure 3 is a rear elevation taken on the line III—III of Figure 1.

30 Referring more particularly to the drawings, the numeral 2 designates the furnace wall, which has a recess 3 formed therein for the reception of the hollow bosh cooling plate 4 and is enlarged at the outer or rear end for the reception of a casing or frame 5.

The plate 4 is preferably tapered toward its forward end to form a wedge shaped 35 structure, thus facilitating its withdrawal in case it is necessary to remove it for replacement or repair. The plate 4 is provided with the usual inlet and outlet openings 6 and 7 to provide for the circulation of water or 40 any other suitable cooling medium there-
through.

The inner face of the frame 5 is cut away or recessed as at 8 to provide a space for a 45 sealing medium 9, such as clay between the side walls of the plate and the frame, and providing shoulders 10 and 11 at each end of the frame.

The rear edge of the plate 4 is provided with a flange 12 adapted to fit against the 50 shoulder 10 and to compress and hold a suitable packing or gasket 14 between the shoulder 10 and plate 4 so as to form a gas-
tight joint between these members.

The frame 5 is adapted to be built per-
55 manently into the furnace wall 2 and the

plate 4 is adapted to be inserted through the frame.

In order to seal and secure the plate 4 in position, I provide a novel means to permit the forcing of a plastic sealing medium, 60 such as clay, into the space between the plate 4 and frame 5 formed by the recess 8. A vertically disposed opening or passage 16 is formed through the rear wall of the plate 4 and opens into the space or recess 8 and a horizontal opening or inlet 17 is provided which opens into the opening or passage 16. The inlet 17 is screw threaded to provide for the connection of screw threaded end of a discharge pipe or conduit 18 leading from a 65 clay cylinder or pump 19. After the plate 4 is positioned in the wall 2 the conduit 18 is connected with the inlet 17 and clay or any other suitable sealing medium is forced through the opening 16 into the space or re-
70 cess 8 so as to completely fill the same and form a perfectly sealed and locked joint between the frame 5 and plate 4.

In order to facilitate the removal or withdrawal of the plate for repairs or replacement I provide two pairs of lugs 21 adapted to be engaged by the T-heads 22 of pulling bolts 23. The bolts 23 are adapted to have their threaded ends project through suitable apertures or openings in yoke members 24 which are engaged against the frame 5 and to have nuts 25 threaded thereon. It will be readily understood that by tightening the nuts 25 on the bolts 23 against the yokes 24 the plate 4 will be withdrawn from the re-
75 cess 3 without disturbing the frame 5 or the furnace wall 2.

In all of the usual bosh cooling plate constructions heretofore used, it is necessary to build them into the wall in order to secure 80 a sealed joint and to remove a portion of the furnace wall when it was desired to repair or replace the plate, while with a plate constructed in accordance with this invention the plate may be inserted, withdrawn and 85 sealed without disturbing any of the brick wall.

I claim—

1. A bosh cooling plate comprising a hollow body portion, inlet and outlet openings 105 communicating with said hollow body portion to provide for the circulation of a cooling fluid therethrough, said body portion being provided with a vertically disposed opening adjacent its rear end and a horizon- 110

tal opening in its rear end intersecting said vertical opening, said openings co-operating to form a passageway to permit the forcing of a sealing medium under pressure around 5 said plate after said plate is in final position.

2. A bosh cooling mechanism comprising in combination a hollow cooling plate having inlet and outlet openings communicating therewith so as to provide for the circulation of a cooling medium therethrough, a frame into which the rear end of said plate projects, said plate being provided with an opening adjacent its rear end to permit the 15 forcing of a sealing medium under pressure around said plate after said plate is in position in said frame.

3. A bosh cooling mechanism comprising in combination a hollow cooling plate having 20 inlet and outlet openings communicating therewith so as to provide for the circulation of a cooling medium therethrough, a frame into which the rear end of said plate projects, said plate being provided with an 25 opening adjacent its rear end to permit the forcing of a sealing medium under pressure around said plate after said plate is in position in said frame, and means for forming a sealing connection between the rear edge 30 of said plate and said frame to prevent the escape of said sealing medium.

4. A bosh cooling mechanism comprising in combination a hollow cooling plate having inlet and outlet openings communicating 35 with the interior thereof to provide for the circulation of a cooling medium therethrough, a frame member mounted around the rear end of said plate and spaced from the side walls thereof, means for sealing the 40 rear end of said plate against said frame, and means adapted to permit the forcing of a sealing medium into the space between said frame and said plate after said plate is positioned in said frame.

45 5. A bosh cooling mechanism comprising in combination a hollow cooling plate having inlet and outlet openings communicating

with the interior thereof to provide for the circulation of a cooling medium therethrough, a frame member mounted around 50 the rear end of said plate and spaced from the side walls thereof, means for sealing the rear end of said plate against said frame, and an opening formed in said plate to permit the forcing of a sealing medium into 55 the space between said frame and said plate after said plate is positioned in said frame.

6. A bosh cooling mechanism comprising in combination a hollow cooling plate having inlet and outlet openings communicating 60 with the interior thereof to provide for the circulation of a cooling medium therethrough, a frame member mounted around the rear end of said plate and spaced from 65 the side walls thereof, a flange formed around the rear edge of said plate, and a gasket mounted between said plate and said frame and adapted to be compressed by said flange to seal the rear end of said plate against 70 said frame, and means adapted to permit the forcing of a sealing medium into the space between said frame and said plate after said plate is positioned in said frame.

7. A bosh cooling mechanism comprising in combination a hollow cooling plate having 75 inlet and outlet openings communicating with the interior thereof to provide for the circulation of a cooling medium therethrough, a frame member mounted around the rear end of said plate and spaced from 80 the side walls thereof, a flange formed around the rear edge of said plate, and a gasket mounted between said plate and said frame and adapted to be compressed by said flange to seal the rear end of said plate 85 against said frame, and an opening formed in said plate to permit the forcing of a plastic sealing medium into the space between said frame and said plate after said plate is positioned in said frame. 90

In testimony whereof I have hereunto set my hand.

FREDERICK H. N. GERWIG.
